UNITED STATES PATENT OFFICE.

JOHN H. VINTON, OF BOSTON, MASSACHUSETTS, ASSIGNOR TO THE PENINSULAR NOVELTY COMPANY, OF GRAND RAPIDS, MICHIGAN.

BUTTON-SETTING MACHINE.

SPECIFICATION forming part of Letters Patent No. 363,349, dated May 17, 1887.

Application filed October 7, 1886. Serial No. 215,548. (No model.)

To all whom it may concern:

Be it known that I, JOHN H. VINTON, of Boston, county of Suffolk, and State of Massachusetts, have invented an Improvement in 5 Button-Fastening Machines, of which the following description, in connection with the accompanying drawings, is a specification, like letters on the drawings representing like parts. This invention has for its object to provide 10 a button-setting machine of the class represented in United States Patent No. 312,987, granted to me February 24, 1885, with suitable mechanism whereby the same may be operated by power, and also with suitable clutch 15 mechanism whereby only one staple and its attached button can be set by the setting tools or devices at each time the main driving-shaft is engaged and rotated by the clutch mechanism.

20 The invention consists of a cross-head and a button-setting tool operated by its movement, and a crank or eccentric to move the said cross-head, combined with a driving-shaft for rotating the said crank or eccentric, and a clutch 25 mechanism mounted upon the driving-shaft for engaging the continuously-rotating drive-wheel, to thereby rotate the said driving-shaft when desired, the said clutch mechanism being so constructed and arranged that whenever 30 moved into engagement with the main drive-wheel it will there remain to rotate the main drive-shaft a sufficient length of time to permit the button-setting tools or devices to set one button only. I have in this instance 35 loosely connected the treadle-rod with the releasing device, by which the clutch is started or permitted to engage the drive-wheel, so that when the said rod is elevated the releasing device acts to release the clutch, permitting it to 40 engage the main drive-wheel and to thereby rotate the drive-shaft, and immediately after the said releasing device is moved, or at the time the treadle-rod arrives at its most elevated position, the said treadle-rod and releasing device become disengaged, and the releasing device returns to its normal position to check the clutch as it completes its rotation.

45 Figure 1 in front elevation shows a button-setting machine embodying this invention; 50 Fig. 2, a vertical section of Fig. 1, taken on

the dotted line x x ; Fig. 3, a vertical section of Fig. 1, taken on the dotted line y y , also showing the standard and the frame supporting the machine; Fig. 4, a longitudinal section of the clutch, taken on the dotted line z z , Fig. 3; and Figs. 5 and 6, details to be referred to.

The cross-head A , supported by the guide A' , moving in a frame, A'' , has attached to it a button-carrier, A^3 , which co-operates with a stationary anvil, A^4 , the said button-carrier receiving one button and an attached staple from a raceway, A^5 , at each time the button-carrier descends.

Suitable devices, consisting of a detent and 65 let-off attached to the raceway A^5 and operated by projections attached to the moving cross-head, are provided to permit one button and attached staple to pass from the said raceway.

70 The button setting machine herein shown is substantially such as represented and described in the United States Patent No. 312,987, before referred to, and to which reference may be had.

75 An arm, a , leading from the cross-head A , has an eccentric, a' , mounted upon it, about which passes a strap, a'' , of a pitman, a^3 , the opposite end of the said pitman being connected with a crank, a^4 , mounted upon the main 80 drive-shaft b , (see dotted lines, Fig. 2, and Figs. 4 and 5,) said shaft having its bearings in suitable uprights, B B' , attached to any suitable base or frame, B^2 .

85 The main drive-wheel C is mounted upon the drive-shaft b , and a friction-collar, c , is also secured or keyed upon said shaft, against which said drive-wheel C may be moved or brought under such frictional contact as to cause the shaft b to rotate.

90 An abutting collar, D , or it may be, as herein shown, a hub made integral with the shaft b , is located at that side of the drive-wheel C opposite the friction-collar c , said abutting hub carrying two friction-pawls, c' , the ends of 95 which are slightly pointed, as shown in Fig. 5, so that when lying parallel with the longitudinal axis of the shaft b the said points bear so firmly against the drive-wheel C as to force it against the friction-collar c , but when turned 100

slightly on their pivots the said pawls permit the drive-wheel to turn freely.

The upper side of the pawls c' (see Fig. 3) is slabbed off to present two upwardly-inclined surfaces meeting at the longitudinal center to form a sharp edge or rib, which bears frictionally against the interior of a ring, e , surrounding the hub D , the pawls being held in position by the flange c' of the hub D , which is recessed for such purpose, as shown in Fig. 5.

A lug, e^2 , projects from the exterior of the ring e , which strikes against the end of a releasing device or lever, f , pivoted at f' to a frame or support, f'' , said releasing-lever being held in such position by a spring, f^3 , that the lug e^2 may bear against it.

When the releasing device or lever f is moved sufficiently to permit the lug e^2 to pass, the ring e is started by the contraction of a spring, g , (see Fig. 6,) one end of which is connected with a stud or projection, g' , fixed to the ring e , and the other end to a stud or projection, g^2 , fixed to the hub D .

The treadle-rod n passes upward through a hole or opening made in the releasing device f , the end of the said treadle-rod having a shoulder or notch which is normally kept pressed against a holding-plate, n' , by a stud, n^2 , acted upon by a spring, n^4 , a loose connection being thus made between the releasing-lever and the treadle-rod, so that as the treadle-rod is lifted the releasing-lever will be moved sufficiently to release the lug e^2 and permit the pulley C to take with it the drive-shaft.

The treadle-rod having been elevated far enough to lift the lever f and release the lug e^2 , the shoulder of the treadle-rod slips off the plate n' , which permits the releasing-lever to resume its normal position, ready to engage the lug e^2 as it completes its rotation with the ring. After starting the machine the treadle-rod is quickly lowered to again engage the releasing-lever, as shown in Fig. 3, the ring e in said figure being shown as having completed about three-fourths of its rotation. The crank-disk a^4 is cut away or notched, as at a^5 , (see Fig. 2,) to be engaged by a suitable spring-controlled pawl or detent, a' , pivoted to the frame-work, the said pawl preventing backward rotation of the shaft b .

As the said shaft b completes one revolution the lug e^2 will strike the end of the releasing-lever f , and the momentum of the shaft carries it a little farther, sufficiently to permit the pawl a' to engage the notch of the crank-wheel a^4 and to distend the starting-spring g , said spring being thus held distended by engagement with the pawl until the releasing-lever f is again moved to permit the lug e^2 to pass when it contracts, starting the ring e , and by

the frictional contact of the pawls c' moves the said pawls into engagement with the drive-wheel C , forcing the latter against the friction-collar c and thereby starting the drive-shaft.

It will thus be seen that each time the treadle-bar is lifted the shaft b will make one complete revolution and no more, being checked by the releasing-lever f , so that the cross-head A will be moved only sufficiently to permit the button-setting tool or device to set one button.

I claim—

1. In a button-setting machine, a cross-head and button-setting tools or devices operated by its movement, a crank or eccentric, and pitman for moving said cross-head, combined with a driving-shaft for rotating said crank or eccentric, and a clutch-mechanism, substantially as described, mounted upon the driving-shaft for engaging a continuously-rotating drive-wheel to thereby rotate the said driving-shaft, and a releasing-device for permitting the clutch mechanism to rotate, and means, substantially as described, for moving said releasing device and permit it to resume its normal condition, as set forth. 75

2. In a button-setting machine, the button-setting tools or devices, mechanism, as described, for operating them, the crank or eccentric for moving said mechanism, combined with a driving-shaft for rotating said crank or eccentric, and the clutch mechanism, substantially as described, mounted upon the driving-shaft for engaging continuously the rotating drive-wheel to thereby rotate the said driving-shaft, and the releasing-lever having a loose connection with the treadle-rod by which the said releasing-lever is moved, as set forth. 80

3. In a button-setting machine, the button-setting tools or devices, mechanism, as described, for operating them, the notched crank or eccentric for moving said mechanism, and a pawl for entering the notch of said crank or eccentric, combined with a driving-shaft for rotating said crank or eccentric and a clutch mechanism, substantially as described, mounted upon the driving-shaft for engaging a continuously-rotating drive-wheel to thereby rotate the said driving-shaft, and the releasing-lever and treadle-rod normally in engagement with said releasing-lever, but constructed and arranged, substantially as described, to disengage the releasing-lever when rotated. 95

In testimony whereof I have signed my name to this specification in the presence of two subscribing witnesses.

JOHN H. VINTON.
